DOCTOR SWEETENING PROMOTED BY A COPPER SALT

Russell H. Brown, Hammond, Ind., assignor to Standard Oil Company, Chicago, Ill., a corporation of Indiana

Application February 18, 1955, Serial No. 489,093

17 Claims. (Cl. 196—33)

This is a continuation-in-part of my copending application Serial No. 412,706, filed February 26, 1954, now abandoned.

This invention relates to an improvement in the sweetening of sour petroleum distillates by the doctor process.

Owing to the malodorous nature of the mercaptans present in most petroleum distillates, it is necessary to remove these compounds in order to obtain a salable material. Many methods are known for removing the mercaptan odor from mercaptan-containing distillates. These mercaptan-containing distillates are commonly known as sour distillates and the essentially mercaptan-free distillates are commonly known as sweet distillates. The more common processes in use in the petroleum industry convert the malodorous mercaptans to disulfides which are relatively innocuous with respect to odor.

The oldest and probably most common sweetening process now in use is the so-called doctor process wherein an aqueous caustic-sodium plumbite solution and free-sulfur are used to convert the mercaptans to disulfides. The doctor process has many disadvantages which arise primarily from the formation of insoluble lead sulfide. Frequently extremely prolonged settling times are required to remove the PbS from the hydrocarbon oil. Normally not only the doctor solution but also a black-strap layer must be separated from the oil in order to get a PbS-free product oil. The black-strap layer which is a fairly stable emulsion of doctor solution, PbS and oil can be separated only by long settling times or by filtration. Some of the separation difficulties in the doctor process can be overcome by the use of free-sulfur in marked excess of the theoretical amount of 0.5 mol per mol of mercaptan sulfur present in the oil. The amount of excess sulfur used varies with the type of stock.

An additional problem in the use of the doctor process lies in the regeneration of the spent doctor solution for reuse in the process. The doctor solution must be regenerated in order to provide a commercially economic operation. Normally the spent doctor solution is regenerated by contact with free-oxygen at elevated temperatures, e. g., 250° to 350° F. The use of lower temperatures results in extremely long regeneration times.

A further disability of the doctor process lies in the fact that kerosenes and heater oils that have been doctor sweetened generally show an increase in burner deposits as compared with the sour oil.

Despite these disabilities the doctor process is used because for distillates boiling in the heavier-than-gasoline range it is often the only practical way to sweeten particular sour oils.

An object of the invention is to improve the sweetening of sour hydrocarbon oils by means of the doctor process. Another object is to improve the sweetening of sour petroleum distillates which boil in the heavier-than-gasoline range, i. e., between about 325° and 650° F. A further object is the sweetening of sour hydrocarbon oils by an improved doctor process wherein the

2

sweetening reaction and the regeneration reaction are carried out substantially simultaneously. A particular object is the sweetening of a sour heater oil by an improved doctor process wherein the substantially simultaneous regeneration of the doctor solution and the sweetening of the oil takes place and the conventional separate spent doctor regeneration procedure is eliminated. Other objects will become apparent in the course of the detailed description.

10 It is possible to eliminate the separate regeneration procedure of conventional doctor sweetening by using as the sweetening agent a doctor solution containing an effective amount of copper derived from a cupric salt and contacting the sour oil-agent mixture in the presence of at least sufficient free-sulfur to sweeten theoretically the oil and with at least sufficient free-oxygen to theoretically convert the lead sulfide formed to water-soluble plumbite for a time sufficient to sweeten the oil and also to convert the lead sulfide. At the end of this 15 time the agent phase is separated from the oil phase which is essentially sweet and the agent phase which is essentially "regenerated" can be recycled to the sweetening zone.

20 The hydrocarbon oil feed to the process of this invention may be any liquid hydrocarbon oil containing detectable amounts of mercaptans, i. e., oil which is sour to the conventional doctor test or which has a mercaptan number (copper number) above about 1. The process is particularly suitable for the treatment of sour petroleum distillates boiling below about 700° F. Examples of these distillates are naphtha, kerosene, diesel oil, heater oil, gas oil, etc. The process may be used on distillates obtained by the fractional distillation of crude petroleum or on distillates obtained from various conversion processes such as thermal cracking, catalytic cracking, coking, etc. Sour petroleum distillates boiling in the heavier-than-gasoline range, i. e., between about 325° and 650° F., e. g., a heater oil boiling between about 330° and 575° F. are a preferred feed.

25 30 35 40 45 The sweetening agent of this invention consists of a conventional doctor solution and cupric ion derived from a cupric salt. The doctor solution is made up of an aqueous solution of an alkali metal hydroxide and the reaction product of litharge and the alkali metal hydroxide. The plumbite content is commonly given in terms of the percent of PbO theoretically present. This content for a fresh doctor solution is usually between about 1.5 and 2.5% based on aqueous caustic solution. However, it is to be understood that the process is operative with any range of doctor solution compositions that are operable in a conventional doctor process.

50 55 60 65 The promoter used in the process of this invention is a copper compound, believed to contain cupric ion, which is derived from a cupric salt. It is preferred to use a cupric salt which is readily soluble in aqueous caustic solution; hereinafter this preferred cupric salt is referred to as "water-soluble cupric salt." Examples of the water-soluble cupric salts are cupric acetate, cupric bromate, cupric bromide, cupric chlorate, cupric chloride, cupric fluoride, cupric fluosilicate, cupric formate, cupric lactate, cupric nitrate, cupric sulfate, cupric methanesulfonate, cupric ethanesulfonate, cupric benzenesulfonate, and cupric toluenesulfonate. It is to be understood that these salts may be either in the hydrate form or in the anhydrous form. Because of its cheapness, it is preferred to use cupric sulfate in the form of blue vitriol, i. e., the penta-hydrate— $\text{CuSO}_4 \cdot 5\text{H}_2\text{O}$.

70 The copper, derived from the cupric salt, is present in the doctor solution in an amount between about 0.01 and about 0.5 gram per 100 cc. of doctor solution. More usually between about 0.02 and 0.2 gram are present per 100 cc. of doctor solution. When operating with

petroleum distillates boiling in the heavier-than-gasoline range, it is preferred to use on the order of 0.05 gram of copper per 100 cc. of doctor solution, which copper has been derived by adding about 0.2 gram of blue vitriol ($\text{CuSO}_4 \cdot 5\text{H}_2\text{O}$) to the doctor solution.

In order to obtain a sweet product it is necessary to have present in the agent-sour oil contacting zone free-sulfur in an amount in excess of the theoretical. The theoretical quantity of free-sulfur needed for the sweetening reaction is 0.5 mol per each mol of mercaptan sulfur present in the sour oil. For some unknown reason the use of the theoretical quantity of free-sulfur does not produce an oil that is sweet to the doctor test. The amount of excess free-sulfur necessary varies with the sour oil charged and the operating conditions. In general the higher boiling the sour oil, the more excess sulfur that is needed to produce a sweet product. Even with the most refractory feed, this process requires not more than about 175% of free-sulfur theoretically necessary to convert the mercaptans in the sour oil to disulfides. (This is 75% in excess of the theoretical.) In the case of oils that are readily sweetened, it is possible to operate with an amount of free-sulfur barely in excess of the theoretical. Usually the free-sulfur usage will be between about 110% and 175% of the theoretical requirement, i. e., an excess usage of between about 10% and 75% of the theoretical. In order to avoid the presence of corrosive sulfur and to reduce the amount of sulfur compounds present in the sweet oil, it is preferred to operate with between about 110 and 130% of the theoretical requirement of free-sulfur (between about 10 and 30% excess.)

In order to obtain the substantially simultaneous regeneration of the sweetening agent and the sweetening of the sour oil, it is necessary that free-oxygen be present in the contacting zone. The free-oxygen may be introduced in the form of a readily reducible compound such as permanganate or hydrogen peroxide, or free-oxygen itself, or in the form of atmospheric air.

Although the free-oxygen under these conditions accomplishes some mercaptan oxidation, it is primarily present to oxidize the lead sulfide to the water soluble plumbite. Normally, more free-oxygen is introduced into the system than is theoretically required to convert the PbS to the plumbite. In general, the amount of free-oxygen introduced into the sweetening zone is between about 150 and 250% of the theoretical amount of free-oxygen needed to convert the lead sulfide formed in the sweetening reaction.

The temperature at which the sour oil-agent-oxygen-sulfur are contacted may be in general those temperatures used in conventional doctor treating, i. e., between about 70° and 175° F. It is to be understood that the treating temperature may be determined by the flash point of the particular sour oil charged to the process. Thus when operating with naphthas, temperatures on the order of 70° F. will be used; when operating with a kerosene, temperatures between about 100° and 120° F. may be used; and when operating with a high flash point material such as a high boiling furnace oil, temperatures as much as 150° F. or higher may be used. Still another limitation on the contacting temperature may be color formation in the oil, e. g., some kerosenes rapidly develop color bodies when exposed for prolonged times at temperatures above about 120° F. It is preferred to operate at about the maximum temperature permitted by the type of stock used in order to decrease the PbS conversion time. When operating with distillates in the heavier-than-gasoline range, particularly heater oils, it is preferred to operate at a temperature between about 100° and 130° F.; particularly so when using larger amounts of copper promoter. When using smaller amounts of copper promoter, temperatures as high as 150° F. are tolerable without excessive color degradation of the sweet oil.

The contacting time is determined at the lower temperatures by the rate of PbS conversion rather than by the rate of sweetening. At higher temperatures, these reactions proceed more or less simultaneously. The contacting must be maintained for a time at least long enough to both sweeten the oil and to convert substantially all the PbS to the plumbite. It has been found that the conversion of PbS continues after the separation of the agent phase from the oil phase. Thus it is not necessary to carry out the conversion reaction completely in the contacting zone. Usually a completely regenerated agent will be recycled to the contacting zone when the PbS conversion reaction has proceeded to about 95% of completion prior to separation of the agent phase from the oil phase.

The contacting time is favorably influenced by both the temperature, the concentration of caustic in the doctor solution and by the amount of copper promoter present in the doctor solution. The higher the temperature, the shorter the contacting time needed to convert essentially all the PbS . Also, at constant caustic concentration, the higher the concentration of copper promoter derived from cupric salt in the doctor solution, the shorter the contacting time needed to convert essentially all the PbS . Thus, at 70° F. the range of contacting time is between about 1 and 8 hours, the longer times corresponding to the lower copper promoter content. At about 175° F. the contacting times vary from about 5 minutes to 30 minutes, the longer times corresponding to the lower copper promoter content. At about 100° F. the contacting time varies between about 30 minutes and 4 hours; at about 130° F. the contacting time varies from about 10 minutes to about 1.5 hours. Broadly, at constant caustic concentration, the contacting time is related to contacting temperature so that the relationship of time and temperature at a temperature between about 70° and 175° F., the contacting time is between about 5 minutes and 8 hours, wherein the longer times correspond to the lower temperatures.

The alkali metal hydroxide (caustic) concentration in the aqueous solution may be that ordinarily used in doctor sweetening, i. e., from about 5% to 20%, by weight, or more. At constant temperature and copper usage, increasing the concentration of caustic in the doctor solution has a very markedly favorable effect on the rate of regeneration of the PbS formed. At ordinary doctor sweetening temperatures, about 80° F. to 125° F., doubling the amount of caustic in the solution results in more than doubling the rate of regeneration. In order to shorten the time of sweetening-regeneration, it is desirable to operate with doctor-copper solution containing at least about 20% by weight of caustic and preferably between about 25% and about 45%, by weight, of caustic.

The annexed drawing which forms a part of this specification shows an illustrative embodiment of one particular method of utilizing the process of this invention. It is to be understood that the drawing is schematic in nature and many items of process equipment have been omitted since these may be readily added thereto by those skilled in this art.

In the drawing, sour oil from source 11 is passed by way of line 12 into heat exchanger 13. Herein the sour oil is a heater oil boiling between about 330° and 570° F. and has a mercaptan number of 65. This sour oil is derived by distillation from a high sulfur Texas crude. Herein the sour oil is substantially H_2S -free and no pre-wash with aqueous caustic solution is carried out. When the sour oil contains appreciable amounts of H_2S it is desirable to avoid loss of the caustic in the agent by pre-washing the sour oil with aqueous caustic solution.

The sour oil is raised in heat exchanger 13 to a temperature high enough to provide a contacting zone temperature of about 130° F. The hot sour oil is passed from heat exchanger 13 into line 14. A small amount of the hot sour oil is withdrawn from line 14 and is passed

by way of valved line 16 into sulfur drum 17. Sulfur drum 17 is a vessel filled with elemental sulfur such as flowers of sulfur. The hot sour oil dissolves some of this sulfur and the free-sulfur containing oil is passed from sulfur drum 17 into valved line 18. In this illustration, sufficient free-sulfur is dissolved to have present in the sweetening zone about 25% more free-sulfur than the theoretical amount, i. e., 25% excess sulfur.

The sweetening agent from source 21 is passed by way of valved line 22 into line 23. At the start of a run, only fresh sweetening agent will be present in line 23. As the run proceeds the addition of sweetening agent will be limited to makeup quantities. The amount of sweetening agent is at least enough to form a separate sweetening agent phase and may be between about 1 and 20 volume percent based on sour oil. In this illustration, 4 volume percent of sweetening agent is used. The sweetening agent consists of (a) doctor solution composed of about 35% of free sodium hydroxide and about 2 g. of PbO per 100 cc. of solution, and (b) 0.2 gram of CuSO₄·5H₂O per 100 cc. of doctor solution.

Air from source 26 is passed by way of line 27 into line 23. The amount of air present is enough to oxidize the PbS formed in the reaction, i. e., 2 mols of free-oxygen per mol of PbS formed; about a 100% excess of air is introduced. The sweetening agent and the air in line 23 are introduced by way of line 14 into reactor 28.

Reactor 28 is a vertical cylindrical vessel provided with a vent 29 and a motor-driven stirrer 31. The stirrer in this illustration is provided with three turbine blades. In order to improve agitation, reactor 28 is provided with horizontal baffles 32a and 32b.

Although a mechanically agitated reactor is shown herein, it is to be understood that other methods of obtaining intimate contacting may be used, e. g., the reactor may be agitated with air. Also, an orifice mixer which provides a sufficient contacting time may be used.

The order of introduction of sweetening agent and free-sulfur is not a critical feature of the invention. The free-sulfur may be added to the sour oil prior to the introduction of the sweetening agent or the free-sulfur may be added to the mixture of sour oil and sweetening agent. However, it is preferred to mix the sweetening agent and the sour oil before adding the free-sulfur.

The contents of reactor 28, including free-sulfur containing oil from line 18, are maintained at a temperature of about 130° F. for 15 minutes in order to insure sweetening and essentially complete conversion of the PbS. Sweet oil and agent are withdrawn at a trap-out point near the upper end of reactor 28 and are passed by way of line 34 into separator 36. Separator 36 is a substantially horizontal cylindrical vessel providing sufficient settling time for the formation of a separate agent phase and an oil phase. Separator 36 is provided with a vent 37 for the withdrawal of excess air.

The lower agent phase is withdrawn from separator 36 by way of line 39. Normally the agent from line 39 is recycled to reactor 28 by way of lines 23 and 14. The conversion reaction results in the formation of water and sodium sulfate which dilute the agent. Periodically the agent is withdrawn from the system by way of line 39 and valved line 41.

The oil phase is withdrawn from separator 36 by way of line 44. This oil phase contains a very slight amount of occluded agent. The occluded agent may be removed from the sweet oil by either water washing or by coalescing. Herein the oil phase is passed from line 44 into coalescer 46.

Coalescer 46 is a vertical cylindrical vessel provided with glass wool. Instead of glass wool, coalescer 46 may be filled with crushed rock, sand or rock salt. Sweet haze-free product oil is withdrawn from the top of coalescer 46 and is passed to storage not shown by way of line 48.

The agent separated in coalescer 46 is withdrawn from

the bottom thereof by way of line 51. This agent may be recycled to reactor 28 by way of valved line 52, line 39, etc.; or it may be withdrawn from the system by way of valved line 54.

5 The agent withdrawn by way of lines 41 and 54 is preferably treated to recover the lead content. Conventionally the lead may be precipitated by treatment of the agent with hydrogen sulfide and oxidation of the PbS to PbO.

10 It is preferred to prepare the doctor-copper agent by adding a dilute aqueous solution of the copper salt to a well-stirred fresh doctor solution, i. e., one consisting of water, caustic and plumbite. Addition of the copper salt to spent doctor solution containing a large amount of

15 phenolic compounds may result in the formation of oil-soluble copper phenolates which have an adverse effect on the stability of the sweet oil. The buildup of phenols in the solution when sweetening oils containing appreciable amounts of phenols is tolerable under ordinary conditions; however, it is preferred to avoid the formation of solution saturated with phenols.

20 It is to be understood that the embodiment described above is merely one illustration of the use of the process of this invention in the sweetening of a sour hydrocarbon oil. Many variations of the above will be immediately apparent to those skilled in the doctor sweetening art.

The results obtainable with the process of this invention are illustrated by the working examples below.

25 All the experiments described hereinafter were carried out in a three-necked glass flask having a capacity of one liter. The flask was provided with a motor driven stirrer, a thermometer and an electrically heated jacket. Contacting efficiency was improved by means of creases in the sides of the flask. In each run, 500 cc. of sour oil was charged. Except as noted, the doctor solution contained 20 weight percent of sodium hydroxide and 1.8 grams of litharge per 100 cc. of doctor solution. The free-sulfur was added as a one weight percent solution in xylene. Air was bubbled through the liquid in the flask for the 30 regeneration of lead sulfide. The runs were carried out by adding the sour oil and the agent to the flask in that order. Stirring was begun immediately after adding the sour oil. The desired amount of free-sulfur was then added to the agitated mixture of oil and agent. Simultaneously air was bubbled through the liquid in the flask. The agitation was continued until the stirred mixture had become clear and the agent phase had resumed its normal clearness. Tests showed that all the lead sulfide had been converted to water-soluble plumbite when the agent phase became clear. In all runs, the oil was sweet to the doctor test by 35 the time the lead sulfide had been converted.

40 The agent was prepared by adding cupric sulfate pentahydrate (blue vitriol) to the doctor solution. A 5% aqueous solution of copper salt was added to a well-stirred doctor solution at ambient temperature. By this method a deep blue sol was easily made with a minimum of agitation. (The agent was also prepared by adding 20% aqueous cupric sulfate to the doctor solution. However, this concentration formed a blue gelatinous hydroxide which required considerable agitation before the gel formed was peptized to form the desired clear deep blue sol.) Apparently the copper exists in the agent in the form of colloidal cupric hydroxide formed by the reaction of cupric salt and the alkali metal hydroxide present in the doctor solution.

EXAMPLE A

70 The influence of cupric promoter concentration on the time needed to complete the conversion of lead sulfide was studied in this example. In these runs, the sour oil charged was a kerosene having a mercaptan number of 16, i. e., 16 mg. of mercaptan sulfur per 100 cc. of oil and an ASTM boiling range: initial, 350° F.; 10%, 380° F.; 50%, 418° F.; 90%, 461° F.; and maximum, 506° F. In each run, two volume percent of agent was present

based on sour oil; 10% excess free-sulfur was introduced and the contacting was carried out at 120° F. For purposes of comparison, run No. 1 was made with doctor solution in the absence of copper; in this run, the agitation and air bubbling was continued until the black precipitate of lead sulfide had disappeared. In Table I following, the results of these runs are set out.

Table I

Run No.	CuSO ₄ ·5H ₂ O, g./100 cc.-dr. soln.	Cupric ion, g./100 cc.-dr. soln.	Time, Minutes
1.....	none	none	120
2.....	0.1	0.025	60
3.....	0.2	0.05	50
4.....	0.4	0.1	40
5.....	0.8	0.2	40

These data indicate that increasing the amount of cupric promoter present in the sweetening agent accelerates the rate of lead sulfide conversion up to a point where further addition is ineffective.

EXAMPLE B

Two runs were carried out under the same conditions as those of Example A, except that the copper agent was prepared by adding cupric chloride hydrate instead of the cupric sulfate hydrate. In one run, commercial oxygen was bubbled through the flask rather than air. In each run, 0.63 gram per 100 cc. of doctor solution of

was added to the sweetening agent. This corresponds to 0.23 gram of cupric ion per 100 cc. of doctor solution. Run 6 was carried out using air as the PbS oxidizing agent and run 7 was carried out using commercial oxygen as the oxidizing agent. In each run, the PbS conversion time was 35 minutes. These data show that cupric chloride and cupric sulfate are essentially equivalent.

EXAMPLE C

The relationship of copper concentration with temperature of contacting was studied. Herein the sour oil was a heater oil having a mercaptan number of 16 and an ASTM boiling range: initial, 338° F.; 10%, 370° F.; 50%, 432° F.; 90%, 511° F. and maximum, 562° F. The runs were carried out using 4 volume percent of sweetening agent and 50% excess free-sulfur. The results of these runs are set out in Table II.

Table II

Run No.	Cupric ion, g./100 cc.-dr. soln.	Time, Minutes	
		110° F.	130° F.
8 and 9.....	none	480	105
10 and 11.....	0.025	105	45
12 and 13.....	0.05	60	25

These data show clearly the difference in conversion times at lower temperatures between operation with and without the copper. Further the runs show the favorable influence of large amounts of cupric promoter in the agent.

EXAMPLE D

The influence of temperature at constant copper concentration was studied in this example. Herein the heater oil of Example C was used as the charge. The free-sulfur usage was 50% in excess of the theoretical. Four volume percent of agent which had been prepared by introducing 0.2 gram per 100 cc. of doctor solution of blue vitriol, i. e., 0.05 gram of cupric ion were used. The results of these runs are set out in Table III.

Table III

Run No.	Temperature, ° F.	Time, Minutes
12.....	110	60
13.....	130	25
14.....	150	12
15.....	170	9

At the higher temperatures, the rates of sweetening and PbS conversion are substantially the same.

EXAMPLE E

Since color of the sweet oil and color stability in storage of the sweet oil are important in commercial operations, the effect of copper concentration and temperature of contacting on these points was studied. In this example, the runs were carried out using the feed of Example C, 4 volume percent agent and 50% excess free-sulfur usage. In these runs the sweet oil was passed through filter paper to remove traces of occluded sweetening agent. The color of the sweet oil was taken by the Saybolt method immediately after filtering. The color stability of the sweet oil was determined by an accelerated method. 100 cc. of oil were exposed to the atmosphere in an open beaker while being maintained at 200° F. for a total time of 20 hours. The color of the oil was determined and is designated hereafter as "aged color." This accelerated test is known to predict with reasonable accuracy long term storage in tanks vented to the atmosphere. The results of these runs are set out in Table IV.

Table IV

Run No.	Temperature, ° F.	Cupric ion, g./100 cc.-dr. soln.	Sweet Oil, Color Saybolt	
			Initial	Aged
16.....	110	none	25	23
17.....	110	0.025	25	23
18.....	110	.05	25	23
19.....	130	none	25	24
20.....	130	0.25	25	23
21.....	130	.05	25	22
22.....	140	.025	25	23
23.....	150	none	25	24
24.....	150	.025	24	23
25.....	150	.05	22	—1
26.....	160	.025	22	12

EXAMPLE F

In a commercial operation the doctor solution is recycled after regeneration. Therefore, for reasons of economy, it is necessary that improved solutions also be recyclable. In this example, the ability of the sweetening agent of this invention to be recycled was studied under severe conditions. The charge to the runs was a high sulfur heater oil having a mercaptan number of 140 and an ASTM boiling range: initial, 336° F.; 10%, 330° F.; 50%, 430° F.; 90%, 506° F. and maximum, 554° F. This sour oil contains about 0.2 volume percent of phenolic compounds. The sweetening agent contained 0.05 gram per 100 grams of doctor solution of cupric promoter formed by adding blue vitriol to the doctor solution. Free-sulfur was added to the extent of a 25% excess. The temperature of contacting was 140° F. In the initial run, 10 volume percent based on charge of sweetening agent was used. The procedure involved separating the aqueous agent phase from the sweet oil phase and charging the separated agent phase to the sweetening of a fresh portion of the sour heater oil. This was continued until the sweetening agent had been utilized 7 times, that is, separate agent phase had been cycled 6 times. The contacting time needed to convert the lead sulfide was noted in each cycle and the agent phase was analyzed for available PbO content after the final run. The results of these runs are set out in Table V.

9
Table V

Run No.	Time, Minutes	Agent-PbO Content, g./100 cc.
27	30	1.7
27a	30	
27b	30	
27c	30	
27d	36	
27e	36	
27f	30	1.7

These data show that within experimental error the sweetening agent can be reused at least 7 times without loss of efficiency either in the contacting time required or the amount of available plumbite content. This result is obtained without any treatment of the separated aqueous agent phase.

EXAMPLE G

The effectiveness of the process was studied with respect to the sweetening of a light gas oil. This gas oil had been obtained by distillation of crude, i. e., was a virgin gas oil. The gas oil used in the agent sweetened run 29 had a mercaptan number of 10.9 and contained 2.2 mg. of hydrogen sulfide per 100 cc.; the ASTM distillation was: initial, 338° F.; 10%, 374° F.; 50%, 454° F.; 90%, 555° F. and maximum 631° F. Run 29 was carried out at 130° F. using 4 volume percent of agent containing 0.05 gram of cupric promoter and 82% excess free-sulfur. This agent had been utilized in sweetening 6 previous batches of sour oil. The stability of this sweet oil after 4 months' storage at 90° F. in a container vented to the atmosphere was compared to a plant sweetened oil similar to the above virgin gas oil which had been sweetened by conventional doctor technique in the refinery. The results of this comparison are set out in Table VI.

Table VI

	Run Number 29	Run Number 30
Feed, VGO		
Agent, Cycle No.	7	Plant Blend:
Sweet Oil:		Plant doctor:
Color, Saybolt, initial	4	
Color, NPA, 4 mo.	1+	2-
Acid Floc Gum, 4 mo.	4.6 mg./100 ml.	5.0 mg./100 ml.
Sediment, 4 mo.	0.6 mg./100 ml.	0.6 mg./100 ml.

The acid floc gum and sediment determinations were made according to the method of Proell and Bolt, Oil and Gas Journal, March 30, 1946. These results show that even for this higher boiling sour oil, the oil sweetened by the process of this invention is of as good quality as oil sweetened by conventional doctor process.

EXAMPLE H

In order to determine whether or not peroxides, phenols and olefins might precipitate in the process, a run was made under controlled conditions. Dodecane was percolated through silica gel to remove peroxides, phenols and olefins. The dodecane was made sour by adding n-butyl mercaptan to one portion and t-octyl mercaptan to another portion. The sour dodecane were then sweetened using copper containing doctor solution. The reaction proceeded in a manner identical with that when using petroleum distillates as the charge. Apparently, only aqueous caustic and free-oxygen are needed to effect rapid conversion of the lead sulfide.

EXAMPLE I

In this example, the effect of varying the caustic concentration, at fixed copper and temperature, was determined. The feed was a kerosene having a mercaptan number of 17. The doctor-copper agent contained 0.05 g. of copper per 100 cc. of agent; 4 volume percent of agent was used and 127% of theoretical sulfur was used.

10

All runs were made at 100° F. The results of these runs are set out in Table VII below.

Table VII

5	Run No.	NaOH in Dr. Soln., wt. percent	Sweetening-Regeneration Time, Minutes
10	31	30	95
	32	22	120
	33	18	160
	34	16	210
	35	9	300

The decrease in time with increase in NaOH concentration makes it desirable to use caustic concentrations very much higher than those used in ordinary doctor sweetening.

Thus having described the invention, what is claimed is:

1. A doctor sweetening process wherein a sour hydrocarbon oil is contacted with an agent consisting essentially of (a) doctor solution and (b) between about 0.01 and 0.5 gram, per 100 cc. of doctor solution, of copper derived from cupric salt, in an amount at least sufficient to form separate hydrocarbon and agent phases, in the presence of at least the theoretical amount of free-sulfur needed to convert the mercaptans to disulfides, and in the presence of at least the theoretical amount of free-oxygen needed to convert essentially all the lead sulfide formed, maintaining said contacting for a time at least sufficient to sweeten said oil and to convert essentially all the lead sulfide formed, and separating an essentially sweet oil from an agent phase.
2. The process of claim 1 wherein said copper is obtained from a water-soluble cupric salt.
3. The process of claim 2 wherein said salt is cupric sulfate.
4. The process of claim 2 wherein said salt is cupric chloride.
5. The process of claim 2 wherein said salt is cupric acetate.
6. The process of claim 2 wherein said salt is cupric methanesulfonate.
7. The process of claim 2 wherein said salt is cupric benzenesulfonate.
8. The process of claim 1 wherein said agent phase is recycled to the sweetening zone.
9. The process of claim 1 wherein said temperature is between about 80° F. and about 175° F. and said time is between about 5 minutes and about 8 hours, the longer times corresponding to the lower temperatures.
10. The process of claim 1 wherein said oil is a petroleum distillate boiling in the heavier-than-gasoline range.
11. The process of claim 1 wherein said oil is a heavy naphtha.
12. The process of claim 1 wherein said oil is a heater oil.
13. A doctor sweetening process wherein a sour hydrocarbon oil is contacted with an agent consisting essentially of (a) doctor solution containing at least about 20% of caustic by weight, and (b) between about 0.02 and 0.2 gram, per 100 cc. of said doctor solution, of copper formed by introducing a water-soluble cupric salt in said doctor solution, in an amount at least sufficient to form separate oil and agent phases, at a temperature between about 70° and 175° F. in the presence of between about 110% and 175% of the theoretical amount of free-sulfur needed to convert the mercaptans in said oil to disulfides, and in the presence of between about 150% and 250% of the theoretical amount of free-oxygen needed to convert the lead sulfide formed in the sweetening reaction, for a time between about 5 minutes and 8 hours, the longer times corresponding to the lower temperatures, and separating an essentially sweet oil from an agent phase, which agent phase is suitable for recycle to the sweetening zone.
14. The process of claim 13 wherein said temperature is between about 100° and 130° F. and said time is be-

tween about 10 minutes and 4 hours, the longer times corresponding to the lower temperatures.

15. A doctor sweetening process wherein a sour petroleum distillate boiling in the heavier-than-gasoline range is contacted with an agent consisting essentially of (a) doctor solution containing between about 25% and 45% caustic by weight and (b) about 0.05 gram, per 100 cc. of doctor solution, of copper promoter derived by introducing a water-soluble cupric salt in said doctor solution, in an amount at least sufficient to form separate distillate and agent phases, in the presence of between about 110% and 130% of the theoretical amount of free-sulfur needed to sweeten said distillate and in the presence of between about 150% and 250% of the theoretical amount of free-oxygen needed to convert the lead sulfide formed in the sweetening reaction, at a temperature between about 100° F. and 130° F. for a time between about 10 minutes and 90 minutes, the longer times corresponding to the lower temperatures.

5

15 minutes and 90 minutes, the longer times corresponding to the lower temperatures, separating an essentially sweet oil from an agent phase and recycling said agent phase, without further treatment, to said sweetening zone.

16. The process of claim 15 wherein said salt is cupric sulfate.

17. The process of claim 15 wherein said distillate is heater oil.
